DRAIN FITTING

Forest L. W. Link, Silverton, Ohio, assignor to
The Schaible Company, Cincinnati, Ohio, a
corporation of Ohio

Application November 21, 1946, Serial No. 711,401

2 Claims. (Cl. 4—287)

1

This invention relates to improvements in the construction of drain fittings for use in sinks, basins, and the like, and particularly to improvements in the strainer-and-valve type of fitting having two positive normal positions, one fully open and one fully closed.

One of the objects of the invention is to provide a highly serviceable and durable drain fitting of the class described, structurally adapted for economical mass production.

Another object is to provide a drain fitting of the class described, which can be fabricated principally from thin non-corrosive, rust-resisting sheet material by spinning, pressing, stamping and/or punching.

A further object is the provision of a drain fitting of the class referred to requiring no screws, welds, or solder in the assembly of its component parts.

These and other objects and advantages are attained by the means specified hereinafter and illustrated upon the accompanying drawings, in which:

Fig. 1 is a perspective view, partly in cross-section, of the assembled drain fitting in its preferred embodiment, showing the valve in closed position.

Fig. 2 is a fragmentary cross-sectional view of the same fitting, with the valve in open position.

Fig. 3 is a top plan view of the drainage shell.

Fig. 4 is a perspective view of the valve or lifter stem.

Fig. 5 is a view of the valve or lifting stem taken on line 5—5 of Fig. 4.

Fig. 6 is a perspective view of the valve member, partly in cross section to show its construction.

Fig. 7 is a side elevational view, partly in cross section, of the drainage shell assembly of a modified form of the invention.

Fig. 8 is a top plan view of the same.

Fig. 9 is a side elevational view, partly in cross section, of the strainer basket and valve assembly of the modified form.

Fig. 10 is a bottom plan view of the same.

Fig. 11 is a perspective view of the valve support in the modified form of the invention.

In the plumbing art, much effort has been expended to meet a persistent demand for a low-priced yet attractive, serviceable and durable drain fitting for use in kitchen sinks and the like. Heretofore, such drain fittings have been fabricated in a manner that required many costly machining operations, intricate operations in assembly, the application of screws for securing

2

parts together, and so on, all of which necessarily added to the cost of the finished product. This need for a low priced sink drain fitting is largely satisfied by the device of the present invention. Its simplicity of construction and assembly, as will be hereinafter disclosed, permits it to be fabricated by mass production methods at very low cost.

With reference to Fig. 1, the drain structure 10 comprises a drainage shell 15, a strainer basket 16, a valve 17, and a valve or lifting stem 18. The drainage shell 15 may be stamped or otherwise fashioned from a relatively thin sheet of rust and corrosion resistant material, such as 15 Monel metal, stainless steel, silver-nickel, or other material which is characterized by toughness and high tensile strength and which requires no plating. The use of such material has the advantage of giving the fitting an exceedingly long life since it has no plated surface to wear away under the abrasive action of scouring powders and other gritty detergents commonly used to clean kitchen sinks. It is also immune to attacks from various acids and chemicals contained in waste products passing through the drain incident to its use. The shell may comprise a body portion 19 having an annular flange 20, disposed to engage the margins of a suitable aperture provided through the bottom of a kitchen sink, slab, or other area to be drained. The outer wall of the cup-like portion 19 is provided with threads 21 to cooperate with a suitable clamping nut (not shown) for securing the drainage shell to the sink, a suitable washer being usually disposed between the flange 20 and the sink to effect a fluid-tight seal therebetween.

The lower edge of the body portion 19 converges to form a constricted outlet passageway 22, the outer wall of which is threaded as at 23, for engagement with a waste pipe or trap in communication with a sewer or other waste disposal means.

An annular valve seat 25, for cooperation with the valve 17, is provided internally of the passage 22, at the upper perimeter thereof, said valve seat tapering inwardly from a point of maximum width where it intersects the convergent bottom 26 of the shell 15. Integral with the drainage shell is an auxiliary strainer, generally indicated by the numeral 27, said strainer including outlet ports 28 and a central lifting stem support portion 29 depending from the radially extending cross arms 30. As shown in Figs. 2 and 3, the lifter stem support portion is a concentric hemispherical depression at the extreme lower part

of the drainage shell 15, having therein a central elongated aperture 32, said aperture having two parallel straight sides 33 and two other sides arcuated on a common radius, as indicated at 34. The function of the aperture 32, an important aspect of the present invention, will be hereinafter explained. As will be noted from the foregoing, the drainage shell 15, with all its various functional elements, may be stamped or otherwise fashioned from a single piece of relatively thin sheet material, an important factor in the economical production of the device.

Referring again to Fig. 1, it will be noted that the strainer basket 16 and the valve 17 are concentrically mounted on the lifter stem 18, the assembly being disposed for vertical and rotatable movement within the drainage shell 15. The strainer basket 16, cup-like in form and stamped or otherwise fashioned from a thin sheet of rust and corrosion resistant material, is provided with suitable drain holes 35. The upper edge of the basket may be provided with an outwardly extending flange 36, the free outer edge 37 of which is adapted to slide and rotate freely within the body portion of the drainage shell 15. The floor of the basket 16 is centrally apertured as at 44 for engagement with the enlarged diameter 40 of the lifter stem 18.

The valve 17 is simply a disc formed with a downwardly and inwardly turned continuous flange 38, said valve being centrally apertured as at 140 for mounting it upon the diameter 40 of the lifting stem 18. The frusto-conical flange 38 is tapered at an angle to conform to the angle of the valve seat 25 in order to maintain leak-proof relationship when in engagement therewith.

The lifter stem 18 is provided with suitable finger gripping means such as a head 42 at its upper end, for manipulating the strainer basket assembly to open and closed position. Substantially midway of its length the lifter stem is provided with a stop 43, against which the strainer basket 16 abuts when mounted upon the enlarged diameter 40 of the lifter stem, as shown in Figs. 1 and 2. After the valve 17 has been mounted on the diameter 40 of the lifter stem 18, in abutting relation with the bottom face of the strainer basket floor, the shoulder 39 of said lifter stem is peened or rolled over as shown at 41 in Figs. 1 and 2, thereby to firmly secure said basket and valve against rotation or other movement upon the lifter stem 18.

The lower portion 45 of the lifter stem may be provided with opposed parallel flat surfaces 46, giving said portion 45 the same form in cross-section as the form of the aperture 32 in the drainage shell 15 with which it engages when the valve is in closed position, as shown in Fig. 1.

As revealed by a study of Figs. 1 and 2, the valve 17 may be moved toward or away from its seat 25 by grasping the head 42 of the lifter stem 18. If the valve is to be closed, thereby to maintain fluid in the sink, basin, or other fixture to which the drain fitting is attached, the strainer basket assembly is partially rotated by means of the lifter stem head 42 until the lifter stem portion 45 enters the flat sided aperture 32 of the drainage shell 15. At this moment the basket assembly, with the valve 17, gravitationally drops until the valve engages its seat 25, in closed position, as shown in Fig. 1. In this position, the lifter stem portion 45 extends partially through the aperture 32, and by virtue of its relationship with said aperture, is precluded

against rotation therein. In order to open the valve, the basket assembly is raised vertically by means of the lifter head 42 until the lifter stem portion 45 is disengaged from the drainage shell aperture 32, and rotated substantially one-quarter turn, then dropped. At this point, the end face 47 of the lifter stem comes to rest in the hemispherical lifter support member 29, with the flats 46 transversely disposed over the elongated aperture 32 of the drainage shell 15. In this elevated position the valve 17 has become unseated, permitting passage therethrough, as indicated by the arrows in Fig. 2, of waste water or other fluid into the constricted outlet passage-way 22, through the auxiliary drain ports 28 and into a suitable sewage outlet. The strainer basket 16 serves to prevent garbage and other large particles of extraneous matter from entering and possibly clogging the waste pipes leading away from the fitting. The basket and valve assembly is maintained in a firm vertical open position by virtue of the end face 47 being seated in the centrally disposed hemispherical lifter stem support portion 29. In order to remove accumulated waste matter from the strainer basket assembly, said assembly may be lifted from the drainage shell 15, and quickly and easily replaced to either open or closed valve position.

The end face 47 of the lifter stem 18 may be provided with a spherical radius in conformance with the radius of the lifter stem support portion 29 in which it seats when the valve 25 is in open position, as indicated in Fig. 2.

A modification in the structure of the present invention is envisioned, as illustrated by Figs. 7 and 9. The drainage shell 115, fabricated of material similar to that used in the embodiment previously described, is stamped or otherwise fashioned with a downwardly extending flange portion 116, said flange having an inwardly extending annular lip 117. Pressed into the flange portion 116 is an exteriorly threaded tubular coupling member 118 having an outwardly extending flange 119, the annular edge 120 of which is firmly embraced in leak-proof relation by the inner wall of the flange portion 116 by means of the aforementioned pressing operation. To maintain the leak-proof relationship between the coupling member and the drainage shell, a suitable gasket or washer 121 may be interposed between the waste tube flange 119 and the drainage shell lip 117, as indicated in Fig. 7. The body portion 122 of the drainage shell 115 includes an annular flange 123, provided for engaging the margin of a suitable aperture in a sink, tray or other area to be drained. Leak-proof relationship between the sink and the drainage shell may be attained by the application of a suitable washer 124 between the flange 123 of the shell and the upper face of the sink bottom to which the fitting is fixed.

The valve seat member 125 is pressed into the upper opening of the coupling member 118, as at 126, where it is frictionally held against rotation. An outwardly extending flange 127 on the valve seat member serves as an abutment which limits the extent to which said valve seat member may be pressed into the coupling part 118. Integral with the valve seat member are the radially extending spaced arms 128, which serve to support the drainage basket assembly 129 when the valve 130 is in open position.

An annular valve seat 131 is provided internally of the member 125, said valve seat tapering inwardly at an angle conforming to the

tapered periphery 132 of the valve 130 with which it engages in closed and fluid tight relationship.

The strainer basket assembly 129, which is adapted to be removably positioned within the drainage shell 122, in a manner similar to that shown in Fig. 1, comprises a strainer basket 133, a valve 130, and a basket support 134, all concentrically mounted on a lifter or valve stem 135.

The cup-shaped strainer basket 133, suitably fashioned from a thin sheet of rust and acid resistant material, is provided with drain holes 138 and an out-turned annular flange or guide rim 139 for engagement within the upper wall portion 140 of the drainage shell body 122.

The disc-like valve member 130, provided with the hereinbefore mentioned annular tapered peripheral portion 132, is also provided with a recess 141 for disposition therein, in abutting relationship, of the basket support 134, as indicated in Fig. 9.

The basket support 134, shown in Fig. 11, may include a flange 142 depending from its periphery. This flange is provided with a series of depending lugs 149, with intervening spaces 143, the number of lugs being equal to the number of radial arms 128 in the valve seat member 125. The basket 133, the valve 130, and the support 134 are all centrally apertured as indicated at 145, 146, and 147 respectively, said apertures being of equal diameter for concentric disposition on the lower portion 148 of the lifter stem 135. The floor of the strainer basket 133 abuts a shoulder 159 on said lifter stem, while the upper face of the valve member 130 abuts the bottom of the basket 133. The support member 144 is disposed within the recess 141 of the valve 130, and the three parts 133, 130, and 134 are secured in their relative positions by rolling or peening over the peripheral edge 136 of a recess 137 formed in the bottom face of the lifter stem 135, as illustrated in Fig. 9.

In normal open position, the flat bottoms 150 of lugs 149 rest transversely on the radially extending arms 128, thus supporting the basket assembly 129 in an elevated position. When the basket assembly is so disposed, the valve 130 is unseated, thereby permitting free flow of waste water into and through the tubular waste member 118. In order to close the valve, thereby to maintain fluid in the sink or other fixture to which the fitting is applied, the basket assembly is partially rotated until the lugs 149 disengage from the drainage shell arms 128 upon which said lugs rest. At this moment the basket assembly will drop, bringing the valve 130 upon its seat 131, in fluid-tight relationship. In this closed position, the lugs 149 are disposed within the drainage ports 152 of the drainage shell, with the spaces 143 of the basket support 134 straddling the radial arms 128 of the drainage shell. The basket assembly may be lifted or rotated by means of the head 153 of the lifter stem, said head being suitably formed to provide finger gripping means.

In order to clean the strainer basket 133 of refuse, the strainer basket assembly is lifted out of the drainage shell by means of the head 153 of the lifter stem. The basket assembly is then replaced to its normal open or closed valve position.

From the foregoing it is obvious that there is provided a simple and positive acting drain

fitting which may be very economically manufactured and assembled, and which, once assembled, is trouble free, since there are no pins or other delicate parts to become damaged or broken. It should also be noted that the valve is not given to rotary motion relative to its seat when it is seated or unseated, since the valve is constrained to move vertically toward or away from its seat, thereby eliminating wear between the cooperating valve members.

It is to be understood that various structural changes and modifications may be made within the scope of the appended claims, without departing from the spirit of the invention.

15 What is claimed is:

1. In a sink strainer, the combination of a unitary cup-shaped shell comprising a peripheral flange for supporting the fitting, a side wall, and a partly open bottom including a central portion having a spherical curvature concaved upwardly, the spherically curved portion having a central aperture having at least one flat side, an annular valve seat on an intermediate surface of the shell, a cup-shaped strainer basket mounted for vertical movement and being rotatable inside the shell, a stem extending from the bottom of the basket coaxially therewith and secured thereto, said stem having its lower end adapted to slide through said central aperture, said lower end having at least one flat side adapted to engage the flat side of the aperture of the shell when the lower end of the stem is in the aperture, the end surface of the lower end of the stem being curved to correspond to the spherically curved surface of the bottom of the shell, the spherically curved tip of the stem being adapted to rest in the spherically curved portion of the shell to support the basket in an elevated position, a valve disc attached to the lower side of the basket and adapted to engage the valve seat when the basket and the stem are in lowered position, the valve disc and seat being disengaged when the basket and stem are in elevated position, the stem and basket being rotatable in the shell when in elevated position to bring the flat surfaces of the shell and the stem into alignment to permit the basket and stem to fall to bring the valve disc and valve seat into engagement.
2. A sink strainer in accordance with claim 1 characterized by the fact that the bottom of the shell as defined by the spherically curved portion of the shell is attached to the shell wall by spaced radial arms and that perforations are provided between the spaced radial arms to permit flow of fluid through the bottom of the shell when the basket and stem are in elevated position.
